UNITED STATES PATENT OFFICE.

LOUIS H. LANDRY, OF UXBRIDGE, MASSACHUSETTS, ASSIGNOR OF ONE-HALF TO SAMUEL B. TAFT AND ONE-EIGHTH TO UDGIL LACOCQUE, BOTH OF UXBRIDGE, MASSACHUSETTS, AND ONE-EIGHTH TO LOUIS BOUSQUET AND THEODORE BOUSQUET, BOTH OF BURRILLVILLE, RHODE ISLAND.

BOX-MOTION FOR LOOMS.

1,184,859.

Specification of Letters Patent.

Patented May 30, 1916.

Continuation in part of application Serial No. 445,155, filed July 24, 1908. This application filed August 14, 1909. Serial No. 512,784.

To all whom it may concern:

Be it known that I, LOUIS H. LANDRY, a citizen of the United States, residing at Uxbridge, in the county of Worcester and 5 State of Massachusetts, have invented a new and useful Box-Motion for Looms, of which the following is a specification.

This invention relates to a box motion, and this case is a continuation in part of 10 my United States Patent on a loom, No. 943,028, granted on the 14th day of December, 1909, on an application filed July 24, 1908, Serial No. 445,155, and is in part an improvement thereon.

15 The principal objects of this invention are to provide a simple and inexpensive construction of box motion which will open and close the levers without the use of vibrator gears, and which will operate independently of the drive of the picker; to provide an improved and simplified arrangement of raising and let-down levers, and of operating connections therefor, and an improved arrangement of levers to be 20 operated thereby for controlling the motions of the box; to provide a new and improved dividing lever connection for the long and short levers for operating the boxes; to provide an improved locking arrangement for 25 the let-down levers; to provide means whereby the let-down levers can be held up out of the way when desired; to provide improved means for attaching the box to the box rod connected on the underside so that 30 the box cannot rock; and to provide a construction of box adapted to operate up and down and take the guide in a vertical path.

Further objects and advantages of the invention will appear hereinafter.

40 Reference is to be had to the accompanying drawings, in which—

Figure 1 is an elevation of one form of operating mechanism for the box motion; Fig. 2 is a plan of the same; Fig. 3 is a 45 front elevation showing how the box may be connected with said box motion; Fig. 4 is an elevation of another embodiment of the invention; Fig. 5 is an elevation of a detail thereof; Fig. 6 is a plan of a portion of the 50 driving mechanism shown in Fig. 4; Fig. 7 is an end elevation of a part of the box supporting and operating connections; Fig. 8

is a front view of a portion of a shuttle box showing how it is connected with the box-rod; Fig. 9 is an elevation of a portion of 55 the parts shown in Fig. 4 with the outside elements removed to show interior construction, the same being partly in section; Fig. 10 is a similar view of certain parts thereof with further elements removed; Fig. 11 is 60 a plan of a detail of the guide shown in Fig. 9. Fig. 12 is a plan of the raising levers; and Fig. 13 is a plan of the operating chain.

The first four figures represent the matter 65 divided out of my above mentioned application and patent, and the remainder of the figures represent certain improvements thereon which embody and carry out the same principles.

70 In the form shown in the first three figures, the box motion is driven from the eccentric shaft 114 through an eccentric 165. The shaft 114 can be operated by power 75 when the loom is stopped. The eccentric rod connected with it operates a link 166 which reciprocates a block or frog 167 to slide in ways 168 on the frame. The box motion is controlled in a way similar to that shown in Figs. 2 and 3 of my above said patent for 80 opening the shed but in this case there are four tilting frames 170 each having a pair of hooks 171 constituting raising levers and let-down levers, above and below the block 167 and sufficiently far apart to prevent 85 both of them engaging the block at the same time. Under the frame 170 or preferably under the lower hook are located a series of operating vibrator levers 172 which are controlled by a chain cylinder 173 on the shaft 90 107. The rotation of the shaft 107 actuates the levers 172 through the chain cylinder 173 in the same manner as that described above with reference to the other chain cylinder 150 and causes any one or more of the 95 frames 170 to be tilted up so that their lower hooks engage the block 167 and move with it. The frames 170 are provided with projections 174 engaging rollers 175 on a corresponding number of bell cranks 176. 100 These bell cranks operate links 177 two of which are supported on long pivoted levers 178 and the others on short levers 179 which operate swinging sprocket wheels 180. These

sprocket wheels engage chains 181 fixed adjustably to the levers 178 and pull the shuttle box 182 up a greater or less distance according to which ones of the frames 170 are moving up. It will be seen that the links 177 are shown as of two different lengths to provide for four shuttles and four positions of the shuttles and four positions of the shuttle box. This can be varied in case a different number of shuttles is employed. This mechanism is shown in connection with a box rod 183 and spring 184 for guiding and controlling shuttle boxes in the box guides 185. A lock 186 on the shaft 187 acts to hold the levers 172 like the lock 158, of my above mentioned patent.

Referring now to Figs. 4 to 13 inclusive, this form of the invention will be described in greater detail. The main shaft (not shown) drives the chain cylinder shaft 20 on which is a gear 21 represented by dotted lines running a gear on a shaft which by bevel gears rotates an upright shaft 23. The shaft 23 is shown as driving a shaft 24 by means of bevel gears, and connected with the latter shaft are eccentric gears 25 and 26 which rotate a horizontal shaft 27 carrying an eccentric 28. The object of the eccentric gear is to provide a construction in which the speed of the shaft 27 can be made to vary during a complete rotation so as to raise the boxes slowly and drop them rapidly.

On the eccentric 28 is mounted an eccentric strap 29 connected with a cam lever 30 which operates a swinging lever 31 pivoted to the frame of the loom. This lever is shown as pivotally connected with a sliding block or frog 32, which is provided with a longitudinal slot 33 therein through which projects a guide 34 which is mounted on the frame and has a plate 35 on the outer end to keep the frog in position on the guide. This frog is shown as having two projections 36 on opposite sides.

The chain cylinder 40 which is mounted on the shaft 20 is provided with the usual operating chain 41 as is well understood in this art. This chain is designed to lift in turn a plurality of vibrators or levers 42 pivoted on a rod 43. In the present case four of these levers are shown, each one having a spring 44 for normally pulling it down on the chain of the cylinder. Each lever has a projection 45 adapted to engage in a way on the bottom of a raising lever 46 so that when the chain raises one of the vibrators, the corresponding raising lever will be raised. Each of these raising levers is shown as provided with a slot 47 passing over a shaft 48 on the frame so as to permit the raising lever to move back and forth. Each of the raising levers has a cam surface 49 on its upper side along which slides a projection 50 on a let-down lever 51. The surface 49 gradually rises toward the right so that as the let-

down lever is pulled back it gradually rises and finally becomes disengaged from the projection 50. The raising levers and let-down levers are provided with projections or teeth 52 and 53 respectively, which are engaged by the projections of the frog as the latter reciprocates. When any one of the vibrators is permitted to rest back on the chain cylinder on account of the absence of any roll of the chain at that point, the corresponding raising lever drops down out of the way of the lower projection 50 and at the same time the corresponding let-down lever drops down into position for its tooth to engage the upper projection 50. Normally spring levers 54 press down on the let-down levers to hold them in position to engage the frog, but if desired they can be locked up out of the way by means of a projection 55 on each one and a gravity lock latch 56 for engaging these projections. These projections extend out so as to be easily moved by the finger. This lock is used when it is desired to hold these levers up out of the way for repairs or any other purpose.

Certain of the raising levers 46 extend back of the shaft 48 and are pivoted to short levers 60. The others extend farther back and are pivoted to long levers 61. Both the short and long levers are mounted to swing freely on a shaft or stud 62 fixed to the frame. Also mounted to swing freely on this shaft or stud is a connecting lever 63 which extends below the shaft 62 and has a curved portion extending above it. To the upper end of this curved portion is pivoted a dividing lever 64. This dividing lever extends in both directions from its pivot and engages a stud 65 on the short lever and a stud 66 on the corresponding long lever. The distances from the center of the dividing lever to these points of contact with the two studs 65 and 66 are equal.

The operation of this part of the device is as follows: When the frog moves to the right, the lower projection 50 thereon will engage one or more of the teeth 52 on account of those levers being raised by the chain. Consequently, the motion of the frog will pull one or more of the levers 46 to the right. The motion of the lower end of the dividing lever 64 will be reduced to a half at its point of application to the connecting lever 63. If the raising lever that is operated is one of those which is connected to one of the long levers 61 the motion of the connecting lever will be twice as great as is the case when a short lever is operated. This is on account of the fact that the distance between the shaft 62 and the stud 66 is twice as great as that between the shaft 62 and the stud 65. It will be understood that in either case one of the studs 65 or 66 remains stationary and serves as a fulcrum for the lever 64. The parts are so designed that

this operation of the short lever moves the box up one step, while the same operation of the long lever moves it up two steps. If it is desired to raise it up three steps, it is necessary to operate both the short and long lever and this will have that effect because in that case both the studs are advanced. The long and short levers are returned to a normal position or moved backwardly to some other position by means of the let-down levers which as has been explained, are operated when the frog moves to the right. This operation takes place in a very simple manner through levers 68 pivoted on the shaft 48 and each connected with one of the let-down levers 51. Each of these levers 68 is connected by a link as 69 with either a short or a long lever. Each lever 68 also has a notch 70 adapted to be engaged by a tooth on a lock finger 71 which is normally pressed upwardly into locking position by a spring 72. The vibrators 42 are provided with projecting fingers 73 which engage over the ends of the lock fingers and unlock the same when the vibrators are pulled down by their springs 44 which are stronger than the springs 72. Each lever 68 has a tooth 740 to limit the backward motion of rotation.

When it is desired to keep the boxes at their highest limit on both sides of the loom so that the shuttle will play back and forth in a single box, which of course is done for weaving selvages or certain simple fabrics, the following mechanism is provided: The several vibrators are provided with operating surfaces 74 which are adapted to be engaged by a projection on the shaft 75 that is operated by a handle 76. This is located adjacent to the comb 77 in the present instance. Another comb 78 is shown at the point where the projections 73 engage the lock fingers.

It will be understood of course that any desired numbers of boxes can be used on each side of the loom but in the present instance the machine is illustrated as having four boxes on each side; consequently there are four vibrators 42; four raising levers; four let-down levers; and four lock fingers all located on the head motion side of the loom, but there is only one connecting lever 63. This connecting lever directly operates the box on that side of the loom as will be described hereinafter, while the box on the other side is operated by a link 780 that extends across the loom and a bell-crank or other lever 79 for transmitting its motion to a rod 80. The corresponding rod 80 on the head motion side of the loom is operated from the connecting lever 63 in any convenient manner as for example, by a lever and arm or bell-crank, as indicated. The rods 80 of the two sides of the loom preferably are connected with the shuttle boxes in

the same way and only one of them will be described.

At its lower end the rod 80 is provided with a loop 81 receiving a lever 82 which is connected by a link 83 with the bottom of the box rod 84, which is adapted to move in a guide 85 on the frame. The box rod is provided with a spring 86 as usual and at its upper end it is shown as having a thin projecting flange 87 provided with a flat top 75 surface, a stud 88, and a projection 89 having a flat surface at the top thereof. The shuttle box 90 rests flat on the top surface of the flange 87, and is provided with an ear 91 registering with the projection 87 and 80 having a perforation for receiving the stud 88. The bottom of this ear fits the flat surface of the projection 89 so that the parts can be readily and accurately placed in their relative positions and then secured together 85 as for example, by screws 92 or the like. On account of these features there can be no rocking of the box on its support even if the screws should get loose.

Connected with the lever 82 is a chain 93 90 which passes under a roller 94 and is connected with a spring 95 to steady the boxes. The springs from the opposite sides of the loom may be connected together if desired or can be independent of each other. The 95 operation of these elements will be obvious. The rod 80 pulls the lever 82 up to lift the boxes, while the spring pulls it down when permitted by the mechanism above described.

While I have illustrated and described two embodiments of this invention, I am aware that many modifications can be made therein by any person skilled in the art without departing from the scope of the invention as 105 expressed in the claims. Therefore, I do not wish to be limited to all the details of construction shown and described, but

What I do claim is:—

1. In a loom, the combination of two 110 shafts, eccentric gears connecting said shafts for driving one of them at a non-uniform rate of speed during a revolution, an eccentric lever or arm connected with said shaft and adapted to be operated thereby, a 115 block or frog connected with said lever, a guide for guiding said block or frog to move in a straight path, and levers on two sides of the block or frog adapted to be engaged thereby, whereby the said levers will be 120 moved with the block or frog.

2. In a box motion for looms, the combination of a block, means for moving the block, a lever adapted to engage the block, an operating lever, means for lifting the operating 125 lever so as to lift the first named lever, means for locking said operating lever in its lifted position to hold the first named lever, means for moving the first named lever back after the operation of the operating lever 130

and block, and means controlled by said block for moving the boxes.

3. In a loom, the combination of a block, means for moving the block, a plurality of levers having projections adapted to engage the block, a series of operating levers, one for each first-named lever, a chain cylinder for lifting the operating levers in a predetermined order so as to periodically lift the

10 first-named levers, means controlled by each of the first-named levers for operating the box motion, means for locking said operating levers periodically in their lifted position to hold the first-named levers, and 15 means for moving the parts back to position after the first-named levers have operated.

4. In a loom, the combination of a reciprocatory block, a guide for grinding said block to move in a straight path, a series of 20 levers having teeth thereon, whereby the motion of the block in one direction will move said levers if they are in engagement with it, means for moving them into engagement with the block, means for controlling

25 said moving means to bring them into action in predetermined order, and a series of levers for moving the parts back to position after the first named levers have operated.

5. In a loom, the combination of a reciprocatory block, a guide for guiding said block to move in a straight path, a series of levers below the block having teeth thereon, whereby the motion of the block in one direction will move said levers if they are in 35 engagement with it, means below said levers for raising them into engagement with the block, means for controlling said raising means to bring them into action in predetermined order, and a series 40 of levers above the block for engaging it and moving the parts back to position after the lower levers have operated.

6. In a loom, the combination of a sliding block, a set of lower levers, a series of vibrators for raising the lower levers into position to be engaged and moved by the block, means for controlling the operation of the vibrators, a set of upper levers adapted to engage the block on its reverse travel, and 50 spring levers engaging the upper levers and normally forcing them toward the block.

7. In a loom, the combination of a sliding block, a series of levers adapted to engage said block and to be moved therewith, spring 55 levers for normally pressing the first named levers toward the block, each of said spring levers having a projection thereon by which the said spring levers can be swung out of contact with the first named levers, and 60 means for locking said spring levers in retracted position.

8. In a loom, the combination of a sliding block, a series of levers below the blocks having teeth for engaging the block, means for 65 selecting certain of said levers and raising

them into contact with the block, and a series of upper levers adapted to engage the block on the reverse motion, each resting on one of the lower levers and movable upwardly independently thereof.

9. In a loom, the combination of a sliding block, a series of levers below the block adapted to be raised individually into contact therewith, each of said levers having a cam track thereon in the side toward the 70 block, a series of levers above the block, each resting on one of said cam tracks and adapted to engage the block when at the outer end of the cam track and to be raised from the block as they move with it over the 75 cam track.

10. In a loom, the combination of a sliding block, a series of levers adapted to be moved individually into contact therewith, each of said levers having a cam track thereon in the side toward the block, a series of 80 levers, each engaging one of said cam tracks and adapted to engage the block when at the outer end of the cam track and to be moved away from the block as they move with it 85 cam track.

11. In a loom, the combination of a movable block, a series of levers having means for engaging the block whereby said levers will be moved with the block, a series of cam 90 tracks for said levers, each rising toward the block, whereby the levers will be raised out of engagement with the block after having traveled a certain distance therewith, a stationary shaft, a series of levers pivoted 95 on said shaft, one connected with each of the first named levers and adapted to be operated thereby, means for engaging the last named levers and locking the parts in position, and a shuttle box mechanism connected 100 with the last named levers.

12. In a loom, the combination of a movable block, a series of levers having means for engaging the block, whereby said levers will be moved with the block, a stationary 110 shaft, a series of levers pivoted on said shaft, one connected with each of the first named levers and adapted to be operated thereby, a shuttle box mechanism connected with the last named levers, each of the last named levers having a notch therein, and a series of 115 spring-pressed levers adapted to engage in said notches for locking the parts in position.

13. In a loom, the combination of a movable block, a series of levers having means for engaging the block, whereby said levers will be moved with the block, a stationary shaft, a series of levers pivoted on said shaft, one connected with each of the first named levers and adapted to be operated thereby, a 120 shuttle box mechanism connected with the last named levers, each of said last named levers having a notch therein, a series of 125 spring-pressed lock fingers adapted to engage in said notches for locking the parts in 130

position, a series of vibrators for operating the first named levers, each having a projection adapted to engage a lock-finger, and resilient means for normally pulling said vibrators and thus removing the locking finger from operative position.

14. In a loom, the combination of a movable block, a series of levers having means for engaging the block whereby said levers 10 will be moved with the block, a second series of levers, one connected with each of the first named levers and adapted to be operated thereby, a shuttle box mechanism connected with the last named levers, each of 15 the last named levers having a notch therein,

and a series of spring-pressed lock-fingers adapted to engage in said notches for locking the parts in position, said levers each having a stop beyond the notch whereby when the lock-finger is released from the 20 notch it will still engage said stop and limit the motion of the other lever.

In testimony whereof I have hereunto set my hand, in the presence of two subscribing witnesses.

LOUIS H. LANDRY.
